UNITED STATES PATENT OFFICE.

JAMES DUNCAN DITHRIDGE, OF NEW YORK, N. Y., ASSIGNOR TO BRYCE BROTHERS COMPANY, OF MOUNT PLEASANT, PENNSYLVANIA, A CORPORATION OF PENNSYLVANIA.

DESIGN FOR A GOBLET OR SIMILAR ARTICLE.

Application filed May 4, 1928. Serial No. 26,562. Term of patent 14 years.

To all whom it may concern:

Be it known that I, JAMES DUNCAN DITHRIDGE, a citizen of the United States, residing at New York city, in the county of New York and State of New York, have invented a new, original, and ornamental Design for Goblet or Similar Article, of which the following is a specification, reference being had to the accompanying drawing, forming part thereof.

The figure is a perspective view of a tumbler or goblet, showing my new design.

The base upon which the goblet rests is an integral part of the goblet.

I claim:

The ornamental design for a goblet or similar article, as shown.

JAMES DUNCAN DITHRIDGE.
